KNITTING DEVICE

Sabel Dunn, Los Angeles, Calif.

Application February 19, 1940, Serial No. 319,704

6 Claims. (Cl. 66—117)

This invention relates to knitting devices, and more particularly to a knitting device which has means incorporated therein enabling design effects to be produced in the garment by carrying into the garment as it is knitted an additional thread or threads.

It is an object of this invention to provide a knitting device including a pair of knitting points connected by flexible cable means and including a thread-carrying means interposed between one of the points and the flexible cable whereby a thread may be carried through the knitting as the knitting progresses.

Another object of this invention is to provide a knitting device including a pair of knitting points adapted to be removably connected to a flexible cable means and which knitting points are of different diameters and where there is interconnected between the smaller knitting point and the flexible cable a thread-carrying means.

Another object of this invention is to provide a knitting device of the two-point flexible cable character with a thread-carrying means which is removably positioned in the knitting device.

Other objects and advantages of this invention it is believed will be apparent from the following detailed description of a preferred embodiment thereof as illustrated in the accompanying drawing.

In the drawing:

Figure 1 is a view illustrating the knitting device embodying my invention.

Figure 2 is an enlarged fragmental view partly in section of the thread-carrying means embodied in my invention illustrating the same as adapted to a knitting point and to the cable illustrated in dotted lines.

Figure 3 is a detached view taken substantially on the line 3—3 of Figure 2.

Figure 4 is a view illustrating the adaptation of the thread-carrying means embodied in my invention as provided at one end with an adapter cap and at the other end with a knitting point, making the same applicable for the sewing up of the knitted garment.

Figure 5 is a sectional end view taken substantially on the line 5—5 of Figure 2.

In the knitting of garments from yarn, it is often found advantageous to carry through the knitted garment, or portions thereof, a thread or threads of other material or contrasting yarn to ornament the same. A knitted garment, particularly as hand-knitted, should be knitted with as near even tension upon the yarn as possible throughout the knitting. Variations in tension

at which the yarn is held during the knitting produces an unattractive garment and the knitting of which is not uniform.

In the high-lighting of a knitted garment with 5 yarn of contrasting colors or with threads of other material, it is essential to so incorporate the additional thread or yarn or other material into the garment as to avoid disruption of the uniform knitting tension maintained throughout the knitting process.

In hand-knitting, this is particularly difficult unless means be provided wherein the thread tension throughout the garment may be maintained substantially the same without the necessity of the knitter endeavoring to vary the tension at which the thread is held during knitting.

The device of my invention enables hand-knitting to be carried out with substantially uniform tension of the yarn throughout the knitting 20 while still enabling me to incorporate in the knitting during the process of knitting threads of other material or yarn in order to ornament the knitted garment or desired portions thereof. Thus in accordance with my invention the knitting device is formed of the knitting points 1 and 2 which are tapered at their points 3 and 4, respectively, through relatively long tapers. The knitting points 1 and 2 are adapted to be removably connected to a flexible cable means 5 as by 25 threading the same to adapters 6 carried at the respective ends of the cable means 5. The knitting points 1 and 2 are connected with the adapter 6 by means of threaded pins 7 carried in the tapered ends 8 of the said points.

The flexible cable means 5 preferably 30 comprises two cable sections 9 and 10 connected together by a swivel means 11 of substantially the construction illustrated in the William H. R. Dunn Patent No. 2,183,791, granted December 19, 1939 for Knitting needle connector.

The points 1 and 2 may also be connected at 35 the end of the cable sections 9 and 10 by means of the connectors of substantially the construction illustrated in the said William H. R. Dunn patent.

In accordance with my invention, I interpose 40 between one of the knitting points 2 and one of the cable sections 9 or 10 a thread-carrying member 12. As illustrated, this thread-carrying member 12 is provided between its ends with an elongated eye 13. The thread-carrying member 12 is of the same diameter as the adapter 6 except for its portion 14 which, as illustrated, 45 may be flattened for ease in milling or cutting the eye 13.

In order to enable the thread-carrying member **12** to be adapted in position between the point **2** and the adapter **6** of either of the cable sections **9** or **10**, the same is provided at one end with a threaded socket **15** adapted to receive the threaded pin **7** of either the points **1** or **2** and is provided at its opposite end with a threaded pin **16** adapted to cooperate with the adapter **6** in removably securing the same between the point **2** and the cable sections.

It will be noted from the foregoing that I have stated that the thread-carrying member is interposed between the point **2** and the flexible cable

5. This is because the point **2** is of a lesser diameter than the point **1**. The variation of diameters between the points **1** and **2** is of particular importance in my invention as is the removability of the points **1** and **2** in their connection with the flexible cable means **5** because it enables me to select the points **1** and **2** of such diameter as to permit the carrying out of the knitting process without attempted variations in the tension which I maintain upon the yarn due to the carrying through the knitting of a thread of other material or yarn passed through the eye **13**. Thus for example when knitting a garment of yarn of ordinary size and texture, I have found it advisable to use a knitting point **2** of a 0-size while the point **1** is of a 6-size point where the thread carried through the yarn during the knitting consists of a plurality of strands of gold metallic thread. Of course the difference in sizes of yarn, the difference in size and character of the thread to be carried through the garment, as well as the difference in size of points used in forming the knitting will require variations in the sizes of points selected. This, however, is a matter with which the knitter soon becomes accustomed and with a little practice is enabled to properly select the required point sizes.

It will also be apparent that as the threads are carried back and forth through the knitted garment being formed that in order to maintain proper knitting operations in carrying the thread through the yarn that it may be desirable to interchange the points **1** and **2** to place the point **2** and the thread-carrier **12** on the other end of the flexible cable when returning in forming the next row of stitches. It will be apparent from the foregoing that during the knitting of a particular garment that different size knitting points may be selected as desired for carrying out such operations as waist Shirring, reduction of the size of the knitted stitches for forming wrist bands, reduced sections for sleeves and the like, while still carrying the ornamenting threads or yarn through the knitting as desired. It will also be apparent that these processes of reduction in the size of the knitted stitches for reducing or increasing the size of the garment sections may be made without dropping or picking up stitches. As the points are changed at the ends of the cable sections **9** or **10**, the stitches already knitted are transferred to the cable sections without liability of dropping any stitch. It will also be obvious that if a draw-string effect is required in any section of the garment, either singular or multiple, that the threads carried through the knitting by the thread-carrier **12** may be utilized for forming the desired draw-string effect.

It will also be apparent that through the use of my knitting device that I am enabled to carry the second yarn through the eye **13** and by tying off the second thread at each end, to shirr into

the base any colored yarn or thread of any fullness to obtain the proper length while still avoiding showing any surplus fullness at either side of the garment I am knitting, also avoiding showing any contrasting color through on the wrong side of the garment.

As illustrated in Figure 4, the yarn carrier **12** may also be utilized in connection with the protector cap **17** threaded upon the pin **16** and a small point **2** threaded at the other end to utilize the combination as a blunt-end sewing needle with which to sew the garment together if desired.

In this specification and in the claims the "thread-carrying means" referred to designates the thread- or yarn-carrying member **12** as distinguished from a threaded member.

Having fully described my invention, it is to be understood that I do not wish to be limited to the details herein set forth, but my invention is of the full scope of the appended claims.

I claim:

1. In a knitting device, the combination of a pair of knitting points, one of a diameter less than the other, flexible cable means and means for removably connecting the knitting points at the ends of the flexible cable means, including a thread-carrying member removably interconnected between the smaller knitting point and the flexible cable means.

2. In a knitting device, the combination of a pair of knitting points, a flexible cable, and means for removably connecting the knitting points at the ends of the flexible cable, including a thread-carrying member removably interconnected between one knitting point and the flexible cable.

3. In a knitting device, the combination of a pair of knitting points, one of a diameter less than the other, flexible cable means and means for removably connecting the knitting points at the ends of the flexible cable means, including a thread-carrying member having an elongated eye therein removably interconnected between the smaller knitting point and the flexible cable means.

4. In a knitting device, the combination of a pair of knitting points, one of a diameter less than the other, flexible cable means having adapters on the ends thereof, and means for removably connecting the knitting points at the ends of the flexible cable means including a thread-carrying member of approximately the same diameter as the adapter interconnecting the smaller knitting point and the adapter at the corresponding end of the flexible cable means.

5. In a knitting device, the combination of a pair of knitting points, flexible cable means having a swivel connection between the ends and means for removably connecting the knitting points at the ends of the flexible cable means, including a thread-carrying member removably connected between the smaller knitting point and the flexible cable means.

6. In a knitting device, the combination of a pair of knitting points, flexible cable means including a swivel means, and means for removably connecting the knitting points at the ends of the flexible cable means, including a thread-carrying member removably interconnected between one of the knitting points and the flexible cable means.

SABEL DUNN
